UNITED STATES PATENT OFFICE.

FRANK C. PROHL, OF MILWAUKEE, WISCONSIN.

TURBINE.

1,266,154.

Specification of Letters Patent.

Patented May 14, 1918.

Application filed March 30, 1917. Serial No. 158,595.

To all whom it may concern:

Be it known that I, FRANK C. PROHL, a citizen of the United States, and resident of Milwaukee, in the county of Milwaukee and 5 State of Wisconsin, have invented certain new and useful Improvements in Turbines; and I do hereby declare that the following is a full, clear, and exact description thereof.

My invention relates to new and useful 10 improvements in smoke consuming devices for furnaces, and is more particularly directed to that type of consuming apparatus which is applicable for use on railway locomotives.

15 The principal object of the invention is to provide an efficient means for conveying the smoke and non-consumed gases from the front of the locomotive back to the fire box.

20 In carrying out this object an improved turbine or the like is used forcing the smoke from the compartment at the front end of the locomotive to the fire box, said turbine being so constructed that it may be operated either by live or exhaust steam.

25 With the foregoing and other objects in view the invention consists in certain novel features of construction, combination and arrangement of parts which will be hereinafter more particularly described and 30 claimed, and shown in the drawing, wherein:

Figure 1 is a partly diagrammatic side view of a railway locomotive equipped with my smoke consuming apparatus, and with the front portion broken away to more 35 clearly show the structure.

Fig. 2 is a vertical transverse section taken substantially on the plane of the line 3—8 of Fig. 1.

40 Figs. 3 and 4 are vertical sectional views taken on the planes of the lines 4—4 and 5—5 of Fig. 5.

Fig. 5 is a horizontal section taken on the plane of the line 6—6 of Fig. 3.

45 In the accompanying drawings my invention is shown applied to a railway locomotive of conventional construction, the same including a shell 1 which incloses a fire box 2, boiler tubes and the like, said boiler tubes terminating at a point spaced from the front 50 end of the shell to provide a smoke compartment 3. The smoke and gases pass from the compartment 3 through a smoke stack 4, their passage therethrough being accelerated by steam from the exhaust pipe 5. The fire box 2 is equipped with the usual grate 6.

In carrying out my invention I have provided means for conveying the smoke and gases from the compartment 3 back to the fire box 2 where they are caused to pass 60 through the fire therein. The means for conveying these gases preferably consists of a pipe or duct 7 of a relatively large diameter which has one end communicating with an off-set pocket 8 which extends from 65 the shell 1 and communicates with the compartment 3. The other end of the pipe extends into the fire box.

A rotary fan 18 is used to force the smoke into the duct 7, the same being geared or otherwise connected with the shaft of a 70 rotor 19. This fan is of a diameter slightly smaller than the inner diameter of the shell 1 and is disposed in the smoke compartment 3 adjacent the forward ends of the boiler 75 tubes. The casing which partially incloses the fan is formed of said shell 1, an end or partition plate 20, and an annulus 21, the outer diameter of the same being substantially equal to that of the plate 20. The last 80 mentioned part 21 is disposed between the fan and the boiler tubes, the smoke which is expelled from the latter being drawn into the fan casing through the central opening of the former by the rotation of said fan. 85 This smoke is driven by the fan blades into the pocket 8 hereinbefore mentioned, from whence it passes through the pipe 7.

The rotor 19 is mounted in a casing 22 which has a vertical pipe section 23 formed 90 integrally therewith. As shown in Fig. 6 the pipe 23 is positioned adjacent one end of the casing and communicates with the interior thereof. The lower end of the pipe section 23 is disposed directly above and 95 connected with the exhaust pipe 5, while its upper end extends upwardly and into the smoke stack 4.

The turbine wheel of the rotor is preferably formed with two sets of blades 24 and 100 25, upon both sets of which steam is adapted to impinge to cause the rotation of the wheel. Steam for engagement with the blades 24 enters the casing through an inlet port 26, while a second inlet port 27 is provided for the admission of steam to engage the other blades, the last mentioned port being disposed adjacent the pipe section 23. The port 26 communicates with the injector mechanism (not shown) and receives live 110 steam therefrom; the other port 27 is connected with the exhaust pipe of the con-

tinuously operated air compressor, (not shown).

It will be seen that the exhaust steam from the main exhaust pipe 5 as it passes through the pipe section 23 will impinge on the blades 25. In some instances it is not desirable to admit this steam to rotate the turbine wheel, therefore a flap valve 28 is provided in the pipe section 23, this valve being operated by a rod 29 which extends to the engine cab. It is obvious that this valve may be thrown into either of the positions shown in Fig. 4, in one of which it bypasses the steam around the rotor, while in the other it will allow the steam to actuate the wheel.

The operation of my invention is preferably carried out as follows:

When the locomotive is standing still, there is no exhaust steam from the main exhaust pipe 5 to operate the rotor, therefore a suitable valve (not shown) is opened to permit live steam from the injector mechanism to enter the port 26, the force of such steam obviously revolving said turbine wheel to operate the fan 18. The steam after acting upon the blades 24 passes out through the casing 22 through a passage way 30 and into the pipe section 23 and thus into the smoke stack. This operation of the turbine wheel is aided by the exhaust steam from the air compressor, the steam entering the casing 22 through the inlet port 27. This steam is, however, not sufficiently great in amount to operate the rotor without the aid of other steam.

After the locomotive has started to run the exhaust steam from the exhaust pipe 5 is ample to operate the rotor, therefore the live steam from the injector is cut off. Regardless of the source of the steam the same will rapidly revolve the turbine wheel and cause the fan to be similarly actuated, thereby drawing the smoke and other gases from the boiler tubes and discharging it into the duct 7 from whence it is forced into the fire box, either above or below a grate as is desired.

When it is desired to discontinue the operation, it is accomplished by moving the valve 28 into the position shown in Fig. 4 in full lines, it previously having been in the dotted line position, and opening the passage way through the partition plate 20, the closure 31 for said opening being then dis-

posed as shown in dotted lines of Fig. 1. The opening and closing of this closure or flap valve 31 is occasioned by actuating a suitable crank 32, the same also being controllable from the engine cab.

Under ordinary conditions the apparatus is in operation continuously during the travel of the locomotive, but when the same comes to rest, the apparatus may be cut off by actuating the flap valve 31 to open the partition.

While I have shown and described a specific apparatus in all of its details associated with a locomotive, it is obvious that I may, without departing from the spirit of my invention, utilize the same in connection with fire-boxes of stationary boilers of various descriptions.

From the foregoing description taken in connection with the accompanying drawings, it is obvious that a very simply constructed smoke consuming apparatus has been produced and that the same may be very effectively used in connection with railway locomotives. Various changes may be made in the form and proportion of the various parts of the apparatus to accommodate its use to locomotives of different types and sizes.

I claim:

In a device of the class described comprising a casing having an opening in its side adjacent one end, a vertical pipe section having an opening in the side for communication with the opening in the casing, a two-part rotor in said casing, one part being adapted to be engaged by fluid passing through said pipe section, a valve in the pipe section to selectively direct said fluid through the pipe section or into the casing against one part of the rotor, and an inlet pipe into the casing adapted to direct fluid against the other part of the rotor, the inner wall of the casing adjacent the last mentioned part of the rotor having a passage way cut therein leading into the first mentioned opening to provide an outlet for fluid from the inlet pipe, whereby to actuate the rotor by fluid from different sources of supply.

In testimony that I claim the foregoing I have hereunto set my hand at Milwaukee, in the county of Milwaukee and State of Wisconsin.

FRANK C. PROHL.
